AIR CONDITIONING SYSTEM

Alwin B. Newton, Minneapolis, Minn., assignor to
 Minneapolis-Honeywell Regulator Company,
 Minneapolis, Minn., a corporation of Delaware

Application November 14, 1938, Serial No. 240,324

6 Claims. (CL 257—3)

This invention relates to an air conditioning system and more particularly to a system for cooling and dehumidifying the air in a space having heat generating means such as incandescent lights located therein.

In many structures being conditioned, such as office buildings, stores, factories, and the like an additional cooling load is placed on the system by reason of the fact that these structures may be provided with a large number of electric lights that are normally kept burning during the occupancy of the building. These lights impose an additional load on the cooling system and in the case of factories, etc., a further load on the cooling system is imposed by reason of the fact that there may be other heat generating apparatus located therein. In accordance with my invention, it is proposed to reduce the cooling load on the system by conveying the heat generated by the lights or other heat generating apparatus away from the space being heated except when the air conditioning apparatus is being operated solely to effect a reduction in the humidity of the space when the temperature of the space is not excessive. A common method of reducing the humidity is to circulate air over cooling apparatus which reduces the temperature of the air below the dew-point thereof and then reheating the air and conveying it back to the space. If the temperature is at a desirable value, the heat generated by the various equipment in the space may be effectively utilized to reheat the air which has been cooled to reduce the humidity thereof.

It is therefore an object of my invention to provide means for normally conveying from the space being conditioned the heat generated by the lights and other equipment in the space except at such times as the air conditioning apparatus is being operated solely in order to reduce the humidity thereof, during which time the heat conducting means will be placed out of operation so that the heat generated by the equipment in the space may be utilized to reheat the air which has been dehumidified.

Other objects and advantages will become apparent upon a study of the specification, claims and appended drawing wherein Figure 1 illustrates diagrammatically one form of a system embodying the principles of my invention, and wherein Figure 2 shows a modification.

Referring more particularly to Figure 1, a space to be conditioned is represented by the reference character 10. A fan 11 driven by a motor 12 is provided for drawing air from the space 10 through the conditioning chamber 13 over the conditioning means 14 which may take the form of an evaporator of a refrigeration system, the cooled and dehumidified air being dis-

charged through the duct 15 and outlet 16 back to the space 10.

The refrigeration system may include besides the evaporator 14 a compressor 18 driven by a motor 19, the outlet of the compressor communicating by means of the pipe 20 with the condenser and receiver 21 from which the refrigerant flows through the pipe 22 into the evaporator 14 under the control of the expansion valve 23. This expansion valve 23 may be of any suitable construction and may be a thermostatic expansion valve of the type illustrated in my copending application Serial No. 192,818, filed February 26, 1938. A pipe 25 connects the outlet of the evaporator 14 with the inlet of the compressor 20.

Located within the space 10, light fixtures 28 and 29 are illustrated. These fixtures are shown as comprising bulbs 30 located within the globes 31, the interior of these globes communicating by means of the ducts 32 with the chamber 33. This chamber 33 has an inlet 34 which may communicate with the outdoor air, there being a suitable filter 35 located adjacent the inlet 34 to remove dirt and other foreign matter from the air entering the chamber 33. Located adjacent the outlet of the chamber 33 is a fan 38 having its inlet connected to a pipe 39 having inlets 40 and 41 located within the light fixtures. The fan 38 may discharge into the outdoor air. It will be understood that as the fan 38 is operated, outdoor air will be drawn into the chamber 33 through the inlet 34 and the interior of the light fixtures 28 and 29, then through the pipe 39 to the fan 38 where the air is exhausted into the outdoors. This circulation of air through the light fixtures will effectively remove substantially all of the heat generated by the bulbs 30 while the fan 38 is in operation so that the heat generated by these bulbs will not be dissipated within the space being conditioned.

Located within the space 10 is a thermostat generally indicated by the reference character 45 and comprising a bellows 46 which may be filled with a suitable volatile fluid and against the upper end of which is biased by means of the spring 47 a lever 48 pivoted at 49. Lever 48 carries a mercury switch 50 provided with terminals 51, 52, 53, and 54. As the temperature in the space 45 falls, the bellows 46 will contract and the lever 48 will be moved downwardly under the influence of the biasing spring 47, and when the temperature has fallen to a low enough value the switch 50 will be tilted from the position illustrated in which terminals 53 and 54 are connected together by the mercury element to the opposite position in which terminals 51 and 52 will be connected together. Also located within the space 10 is a humidity responsive device 60 which may comprise a suitable hygroscopic

element or elements 61, these elements being fixed at one end at 62 and having their other end connected to a lever 63 pivoted at 64 and biased in a clockwise direction by means of a spring 65. Carried by the lever 63 is a mercury switch 66, this switch including terminals 67 and 68. As the humidity in the space falls, the hygroscopic element 61 will contract whereupon the lever 63 will be moved in a counter-clockwise direction against the action of the biasing spring 65, and when the humidity has dropped sufficiently the mercury switch 66 will be tilted to a position wherein the circuit through the contacts 67 and 68 is interrupted. As will be hereinafter set forth, the thermostat 45 and the humidity responsive device 60 each control the operation of the compressor motor 19 and initiate operation thereof whenever the temperature or humidity in the space becomes excessive.

For controlling the operation of the fan 38, a relay generally designated by the reference character 70 is provided. This relay includes a coil 71 and an armature 72 to which is connected switch arm 73 cooperating with a fixed contact 74. When the relay 70 is deenergized, the arm 73 is held in engagement with the contact 74 under the influence of gravity or any suitable biasing means, not illustrated. Upon energization of the relay coil 71, the armature 72 moves toward the left and carries the arm 73 out of engagement with the contact 74. Line wires 76 and 77 may be connected to any suitable source of power, not shown, and are provided for supplying power to the motors 19 and 38 and the relay 70.

Operation

With the parts in the positions illustrated, the temperature and humidity in the space are both excessive. Under these conditions, the compressor motor 19 will be energized by means of the following circuit: from the line wire 76, through conductor 78, contacts 54 and 53 of the switch 50, conductors 80, 81, motor 19, and conductor 82 to the line wire 77. Operation of the motor 19 causes the compressor 18 to circulate refrigerant through the evaporator 14 whereupon the air being drawn thereover by the fan 11 will have its temperature reduced to effect a reduction of temperature in the space 10. If the humidity of this air is excessive, the temperature may be reduced below the dew-point thereof, in this manner effecting a reduction in the humidity of the air in the space 10 in a manner well known in the art. Since the temperature in the space is excessive at this time, it is desirable that the fan 38 operate to ventilate the light fixtures 28 and 29. The relay 70 will be deenergized since the circuit therethrough is broken at the terminal 51 of the mercury switch 50 and the arm 73 thereof will be in engagement with the contact 74. Current will now flow through the motor of the fan 38 from the line wire 77 through conductor 85, switch arm 73, contact 74, conductor 86, fan motor 38, and conductor 87 to the line wire 76. Accordingly, the heat generated by the light fixtures 28 and 29 will be removed from the space 10 so that these fixtures will not impose an additional cooling load on the cooling system.

Assume now that the temperature in the space drops to the desired value, whereupon the mercury switch 50 is tilted in the opposite direction from that illustrated but that the humidity in the space is still excessive. Power will still be supplied to the compressor motor 19 as follows:

from the line wire 76, through conductor 90, terminals 67 and 68 of switch 66, conductors 91, 81, motor 19, and conductor 82 to the line wire 77. The refrigeration system will accordingly be operated so as to reduce the temperature of the air flowing over the evaporator 14 below the dew-point and thus effect the removal of moisture therefrom. At this time the relay coil 71 will be energized as follows: from the line wire 76 through conductor 90, mercury switch 66, conductors 91, 80, contacts 52 and 51 of switch 50, conductor 94, relay coil 71, and conductor 95 back to the line wire 77. The energization of the relay coil 71 will cause movement of arm 73 away from contact 74 whereupon the circuit to the fan motor 38 is interrupted and air will no longer be drawn through the fixtures 28 and 29 so that the heat generated by these fixtures will be dissipated in the space 10. It should be noted that the air which has been dehumidified may be introduced into the space 10 in such a manner that it will pass over the light fixtures 28 and 29 so that this air will be reheated by the lights as it is introduced into the space. In this manner, the humidity of the air is reduced by lowering its temperature below the dew-point and then the heat dissipated by the fixtures 28 and 29 is utilized to again reheat the air. It will be apparent that if these lights should reheat the air above the desired value, the switch 50 operated by the bellows 46 will be tilted back to the position illustrated, thus interrupting the circuit through the relay 70 and causing the fan 38 to again operate to ventilate the fixtures 28 and 29.

If both the humidity and the temperature in the space have been reduced to their desired values, the switches 50 and 66 will be tilted in the opposite direction from that illustrated whereupon the compressor motor 19 is deenergized and the relay 71 is likewise deenergized so that the fan 38 operates to ventilate the fixtures 28 and 29 so that the air in the space will not be heated thereby. It will thus be seen that the refrigeration system is placed in operation whenever the temperature or the humidity in the space becomes excessive. It will also be apparent that the fan 38 is operated at all times except when the humidity is excessive and the temperature is not excessive in which case the refrigeration system will operate only to effect a reduction in the humidity in the space and the heat generated by the fixtures will then be available for reheating the air.

Referring now to Figure 2, this figure shows a modification wherein the fan 38' corresponding to the fan 38 of Figure 1 is allowed to run constantly, the control of the generated heat being obtained by means of a damper which is controlled by the relay 70'. In this figure the discharge of the fan 38' is connected by a duct 95 leading to outside and by a duct 96 leading to the conditioned space. A damper 97 when in the full line position causes the air to be discharged to atmosphere and when in the dotted line position causes the air to be discharged into the space. This damper 97 may be positioned by a 180° type electric damper motor of a type well known in the art. This type of motor includes a three wire control circuit which is controlled by the switch arm 73' and contacts 74a and 74b of the relay 70'. When this relay is deenergized, the switch arm 73' engages contact 74a which causes the motor 98 to position the damper 97 in the position shown for thereby causing the hot air from the lights to be dis-

charged to atmosphere. When the relay 10' is energized due to the space temperature being low, the switch arm 13' engages contact 14b which causes the motor 98 to position damper 97 as shown in dotted lines which causes the air from the lights to be discharged into the space. It will also be understood that any suitable form of air conditioning equipment may be utilized for effecting a reduction in temperature and humidity in the space but my system is particularly applicable where a reduction in the humidity of the air is effected by passing the air over a cooling medium. If desired, manual switch means 99 may be interposed in the circuit to the fan 38 to interrupt operation thereof when desirable as during the heating season, at which time it is, of course, desirable that the heat generated by the fixtures 28 and 29 be added to the space 10.

Having described a preferred form of my invention, many modifications may become apparent to those skilled in the art and it should therefore be understood that my invention is limited only by the scope of the appended claims.

I claim as my invention:

1. An air conditioning system for a space having heat generating means therein, means for preventing heat generated by said generating means from being transferred to the space comprising means for conveying the heat generated by said heat generating means to the outside of the space being conditioned, means for circulating air through the space being conditioned, cooling means for cooling the air being circulated through the space, temperature and moisture responsive means for causing operation of the cooling means whenever there is a need for the removal of sensible or latent heat from the space, and means for interrupting operation of said heat conveying means in response to a demand for operation of said cooling means for the removal of latent heat only.

2. An air conditioning system for a space having heat generating means therein, means for preventing heat generated by said generating means from being transferred to the space comprising means for conveying the heat generated by said heat generating means to the outside of the space being conditioned, means for circulating air through the space being conditioned, cooling means for cooling the air being circulated through the space, humidity responsive means for causing operation of the cooling means when the humidity in the space attains an undesirable value, temperature responsive means for causing operation of the cooling means when the temperature in the space attains an undesirable value, and means for interrupting operation of said heat conveying means when the cooling means is placed in operation solely by the humidity responsive means.

3. An air conditioning system for a space having heat generating means therein, means for preventing heat generated by said generating means from being transferred to said space comprising means for conveying heat generated by said heat generating means to the outside of the space being conditioned, means for cooling and dehumidifying the air in said space, means for operating said cooling and dehumidifying means in response to the attainment of a high tempera-

ture or high relative humidity in the space, and means for interrupting operation of said heat conveying means whenever the cooling means is operated solely in response to a high humidity in the space.

4. An air conditioning system for a space having heat generating means therein, means including fan means and duct means for passing air into heat exchange relationship with said heat generating means and for conveying the air heated thereby out of contact with the air in said space to a point outside of said space, whereby the temperature of the space will not be raised appreciably by said heat generating means during the operation of said fan means, means for cooling and dehumidifying the air in said space, temperature responsive means and humidity responsive means in control of said cooling and dehumidifying means for placing said last men-

tioned means in operation when the temperature or the humidity of the space attains an undesirable value, means normally causing operation of said fan means, and means controlled by the humidity and temperature responsive means for interrupting operation of said fan means only when the humidity in the space is excessive and the temperature of the space is at or below the desirable value.

5. An air conditioning system for a space having heat generating means therein, means including fan means and duct means for passing air into heat exchange relationship with said heat generating means and for conveying the air heated thereby out of contact with the air in said space to a point outside of said space, whereby the temperature of the space will not be raised appreciably by said heat generating means during the operation of said fan means, means for cooling and dehumidifying the air in said space, temperature responsive means and humidity responsive means in control of said cooling and dehumidifying means for placing said last mentioned means in operation when the temperature or the humidity of the space attains an undesirable value, relay means controlling the operation of said fan means and interrupting operation thereof in response to energization of the relay means, and circuit means controlled by the temperature responsive means and the humidity responsive means for causing energization of the relay means only when the humidity in the space is excessive and the temperature in the space is not excessive.

6. An air conditioning means for a space having normally energized lighting means which introduce heat into the space, means for normally ventilating said lighting means in a manner to prevent heat generated by said lighting means from being transferred to said space, means for cooling and dehumidifying the air in said space, means responsive to the temperature and humidity of the air in said space in control of said cooling and dehumidifying means and causing the operation thereof whenever the temperature or humidity of the air in the space becomes excessive, and means controlled by the temperature and humidity responsive means for interrupting operation of the ventilating means only when the humidity in the space is excessive and the temperature is at or below the desired value.

ALWIN B. NEWTON.
